DESIGN FOR A PORTABLE ELECTRIC HEATER

William E. Maxson, Jr., Chicago, Ill., assignor to
Chicago Electric Manufacturing Company,
Chicago, Ill., a corporation of Illinois

Application November 29, 1944, Serial No. 116,606

Term of patent 14 years

(Cl. D81—19)

To all whom it may concern:

Be it known that I, William E. Maxson, Jr., a citizen of the United States, residing at Chicago, Cook County, Illinois, have invented a new, original, and ornamental Design for a Portable Electric Heater, of which the following is a specification, reference being had to the accompanying drawing, forming a part thereof.

Figure 1 is a perspective view of a portable electric heater showing my new design;

Figure 2 is a side view of the heater; and
Figure 3 is a top view of the heater.
The dominant features of the design residue
in the portions shown in full lines.

I claim:

The ornamental design for a portable electric heater, as shown and described.
